INVENTOR:

E. P. McCarthy.

United States Patent Office.

EDMUND P. McCARTHY, OF SAN FRANCISCO, CALIFORNIA.

Letters Patent No. 67,782, dated August 13, 1867.

IMPROVEMENT IN WAGON-SPRING.

The Schedule referred to in these Letters Patent and making part of the same.

TO ALL WHOM IT MAY CONCERN:

Be it known that I, EDMUND P. McCARTHY, of San Francisco, county of San Francisco, State of California, have invented an improved Wagon-Spring; and I do hereby declare the following description and accompanying drawings are sufficient to enable any person skilled in the art or science to which it most nearly appertains to make and use my said invention or improvement without further invention or experiment.

The nature of my invention is to provide a wagon-spring, so constructed that the leaves will not be easily broken, however great the weight or the spring or tension upon them may be. In order to accomplish this object I attach to the inner face of the upper and lower portion of the spring metal cups. Midway between these cups is fixed a rubber ball, by means of a spindle passing through it, and when the spring is brought together sufficiently the ball is held between the cups and receives the weight of the load.

To more fully illustrate and describe my invention, reference is had to the accompanying drawings and letters marked thereon, of which—

Figure 1 is a side sectional elevation, and

Figure 2 is an end view.

Similar letters indicate like parts in each of the figures.

A represents an ordinary elliptic spring with my improvement attached, and consists of two metal cups B B, fastened by plates *a a* to the centre of the inner faces of the upper and lower or main portions of the spring. The cups may be perforated with holes or openings, so as to allow the dust or water to pass through them. An India-rubber or elastic ball, C, is suspended midway between the two cups by means of a vertical spindle or rod, D, which is connected permanently, by a nut and screw, to the upper portion of the spring, while the lower portion of the rod works vertically in a hole made in the lower part of the spring, so that there is no hindrance to the free downward and upward movement of the spring; for this purpose, also, a hole should be made in the axle-bed, so as to allow the rod free play when the spring is heavily loaded. Other devices may be employed to keep the elastic ball in place, so that when the spring is borne down it may be received between the cups, and the object may be very well accomplished by suspending the ball in a horizontal manner by a rod and spiral coils attached to each end of the minor axes or ends of the springs, so that the ball will be received by the cups, without deviating from a straight line as the spring is forced down. But I prefer the method as first described, as being the most certain and effective.

By the use of my spring a much greater load can be carried without the danger of breaking the leaves; and where the springs are very light, with but little weight in the carriage or wagon, they often break by the sudden tension and spring which they are subject to, yet such is not the case where my device is used, as the spring is prevented from being pressed down too far, and still is kept strong and elastic by the rubber ball, and the support furnished by the metal cups and ball will prevent the danger of being thrown from the carriage to the ground should the spring be broken at either or both ends.

Having thus described my invention, I am well aware that blocks or pieces of India rubber have been and are used, placed between the upper and lower portions of the spring, but these are inefficient, and, in many cases, useless, by reason of the liability of their turning or doubling from side to side; also the great distance which they are usually placed from the upper portion of the spring renders them of little utility, except when a wagon is loaded heavily; and again, the cost of supplying these pieces of rubber for a wagon is much greater than the expense of providing and attaching my device. Consequently, I do not claim these blocks of rubber as my invention, but what I do claim, and desire to secure by Letters Patent, is—

The metal cups B B for receiving the ball and supporting the spring, in combination with the elastic ball C, suspended or held in place by the rod D, between the upper and lower portion of the spring, substantially as described.

In witness whereof I have hereunto set my hand and seal.

E. P. McCARTHY. [L. S.]
